US00D967693S

(12) **United States Design Patent** (10) **Patent No.:** **US D967,693 S**
Brunner et al. (45) **Date of Patent:** **** Oct. 25, 2022**

(54) **MOUNTING PLATE**

(71) Applicants: **KETER PLASTIC LTD.**, Herzliya (IL); **MILWAUKEE ELECTRIC TOOL CORPORATION**, Brookfield, WI (US)

(72) Inventors: **Yaron Brunner**, Kibbutz Gvat (IL); **Izhar Shany**, Kibbutz Gvat (IL); **Uri Parizer**, Kibbutz Hukok (IL); **Ayala Vardi Bougat**, Kefar Veradim (IL)

(73) Assignees: **KETER PLASTIC LTD.**, Herzliya (IL); **MILWAUKEE ELECTRIC TOOL CORPORATION**, Brookfield, WI (US)

(**) Term: **15 Years**

(21) Appl. No.: **29/702,870**

(22) Filed: **Aug. 22, 2019**

Related U.S. Application Data

(63) Continuation-in-part of application No. 29/681,497, filed on Feb. 26, 2019.

(51) **LOC (13) Cl.** **08-08**

(57) **CLAIM**

The ornamental design for a mounting plate, as shown and described.

DESCRIPTION

FIG. 1 is a top perspective view of a first variant of a new design for a mounting plate;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a second variant of a new design for a mounting plate;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The part shown in dashed lines in FIGS. 7, 8, 13, and 14 form no part of the claimed design.

1 Claim, 10 Drawing Sheets
